(No Model.)

J. KNIGHT.

MECHANISM FOR OPERATING STATION INDICATORS.

No. 394,074.

Patented Dec. 4, 1888.

UNITED STATES PATENT OFFICE.

JOHN KNIGHT, OF SAN FRANCISCO, CALIFORNIA, ASSIGNOR TO THE PACIFIC INDICATOR COMPANY, OF CALIFORNIA.

MECHANISM FOR OPERATING STATION-INDICATORS.

SPECIFICATION forming part of Letters Patent No. 394,074, dated December 4, 1888.

Application filed May 4, 1888. Serial No. 272,825. (No model.)

To all whom it may concern:

Be it known that I, JOHN KNIGHT, of the city and county of San Francisco, State of California, have invented an Improvement 5 in Station-Indicators; and I hereby declare the following to be a full, clear, and exact description of the same.

My invention relates to the class of indicators for use in the cars of street and other 10 railways, for the purpose of designating successive streets or stations and presenting to view at the same time any suitable advertising or display matter.

My invention consists, generally, in the 15 novel mechanism for operating the indicator, and particularly in the construction, arrangement, and combination of parts, which I shall hereinafter fully describe.

The object of my invention is to provide 20 for a simple and effective mechanism for transmitting to the indicating apparatus the power derived by contact with a fixed obstruction in the roadway, and yet so modify the power in strength and time of transmission 25 as to render its application noiseless and without suddenness or jar.

Referring to the accompanying drawing, the figure is a side elevation of my device, the cylinder B being shown in section.

30 A is the floor of the car, upon which is secured an air-cylinder, B, having in one end an inwardly-opening valve, b, and a regulating air-cock, C. Within the cylinder a piston, D, operates, the rod d of which passes through the other end of the cylinder and carries upon it an actuating-spring, E, whose tension is regulated by the sliding collar e. It will now be seen that if a pull be made upon the end of the piston-rod d air will be 35 drawn into the cylinder through valve b, and the spring E will be compressed. As soon as the pull is relieved, the spring will move the piston D back; but this movement instead of being sudden may be perfectly graduated 40 as to time by properly handling the air-cock C to control the air-cushion within the cylinder. This movement of the piston-rod is transmitted to the indicating apparatus by the following mechanism:

45 50 The indicating device, forming no part of

this application, is here simply shown in outline as a box, F, having an operating-pulley, f, from which a chain, f', extends.

G is a shaft having on one end a sprocket-pulley, g, for the chain f'. This shaft also 55 carries a disk, H, from the face of which project pins h. Upon the piston-rod d is a block, I, having pivoted to it a trip-arm, i, one side of the base of which is curved and the other is straight, whereby said arm may 60 move on its pivot in one direction only. A spring, i', returns the arm to an upright position. Now when the pull is made on the piston-rod the trip-arm is carried along with it, and coming in contact with one of the pins 65 h, which stands in its path, it simply yields on its pivot to pass the pin without affecting the position of the disk H; but when the pull is relieved and the arm comes back with the gradually-returning rod it again comes 70 in contact with the pin h, and in this direction it cannot yield. It therefore carries the pin before it, thus moving, at the speed and with the power desired, the disk H, and through it the shaft G, and transmitting the 75 motion through the chain f' to the indicating apparatus. This continues any length of time, according to the proper control of the air-cushion, as described, and at the end the arm pushes the pin h up out of the way, but 80 brings the succeeding pin into its path for the repetition of the operation. In order to accurately check and hold the disk H in the position to which it is moved, I project from the face of the pulley g the pins h', which 85 engage a fixed notched spring, h², at the end of each movement of the disk. The tension of this spring is sufficient to check undue momentum of the disk and to hold it steady until operated.

90 Power is transmitted to operate the piston-rod by the following mechanism: In the roadway is a fixed lug or obstruction, Z, in the shape of an inclined plane. Such a lug is placed at suitable intervals along the road. 95 Pivoted at j to the truck a of the car is a bracket, J, the other end of which is supported and can be adjusted by a depending rod, K, secured above to the car or a fixed frame and having an adjusting-nut, k, on its 100

top. This rod is encircled by a spring, k' , which bears down on the bracket and serves to return and hold it in proper position. Mounted on a shaft, l , in bracket J is a chain-pulley, L , from which the chain l' passes up and over suitable directing-pulleys to the end of the piston-rod d , to which it is secured.

Fixed to the side of the pulley L is a sector, M , the rim of which projects beyond the rim l of the pulley. The spring k' is so adjusted as to press down the bracket, (primarily adjusted by the rod K), so that the sector M shall be held well down to the plane of the obstruction Z in the roadway. When it comes in contact with this obstruction, the contact, though a yielding one, and consequently without jar, is sufficient to effect the movement of the sector and thus partially rotate the pulley L , which through the chain l pulls on the piston-rod d above. The contact of the sector with the obstruction is so timed that the former is turned to its end by the time the end of the latter is reached; but this need not be accurately determined, for if the obstruction be too long it is obvious that the motion of the sector will cease upon its end being reached, and it will simply drag the remainder of the way on the obstruction; but the length of the arc of the sector determines the desired amount of movement to be given to the piston-rod above. As soon as the sector is free of the obstruction, the return movement of the piston-rod turns it back to position again, this position being defined and limited by a slot, m , on the sector coming in contact with the bracket J .

Although I have herein described and illustrated but a single set of these devices, it will readily be seen that in practice a double set is needed, so that the indicator may be operated in reverse manner upon the return trip of the car. I need only say, therefore, that in practice I would have a second air-cylinder with its piston-rod and connections, and a second disk, such as A , with its pins, a second set of fixed obstructions, sectors, pulleys, and connecting-chains, all so arranged as to operate in the reverse direction. One set is therefore inoperative when the other set is working. This second but reversed set of devices I have not deemed it necessary to illustrate, as the arrangement is obvious and customary in this class of mechanism in one form or another.

Having thus described my invention, what I claim as new, and desire to secure by Letters Patent, is—

1. In a station-indicator, the reciprocating rod d , operated by fixed stops in the road and connections between said stops and piston-rod, and the pivoted trip-arm carried by the rod and arranged to move on its pivot in one direction only, in combination with the disk having pins projecting into the path of the trip-arm, whereby said disk is turned on its axis, transmitting-connections from the disk

to the indicating apparatus, and the means for controlling the movement of the rod in one direction, for the purpose described, consisting of the valved cylinder having the controlling-cock and the piston within the cylinder on the end of the rod, substantially as herein described.

2. In a station-indicator, the reciprocating rod d , operated by fixed obstructions in the road and connections between said stops and piston-rod, the spring for returning the rod, and the pivoted trip-arm carried by the rod and arranged to move on its pivot in one direction only, in combination with the disk having pins projecting into the path of the trip-arm, whereby said disk is turned on its axis, transmitting-connections from the disk to the indicating apparatus, and the means for controlling the movement of the rod when returned by the spring, consisting of the valved cylinder having the controlling-cock and the piston within the cylinder on the end of the rod, substantially as herein described.

3. In a station-indicator, the indicating apparatus, an air-cushion, with its piston and piston-rod, and the mechanism for receiving motion by contact with a fixed obstruction in the roadway, and transmitting-power consisting of the pulley suspended by a bracket from the car, the sector connected with the pulley and arranged to roll on the obstruction, the stop m on the sector, whereby the return of the pulley is limited and defined by contact with the bracket, and a connection between the pulley and piston-rod, substantially as herein described.

4. In a station-indicator, the combination of the indicating apparatus, the air-cushion, with its piston and piston-rod, and the mechanism for receiving motion by contact with a fixed obstruction in the roadway, and transmitting-power consisting of the chain-pulley suspended from the car, a chain leading from the pulley to the piston-rod, and the sector secured to or formed with the pulley and arranged to roll on the obstruction, substantially as herein described.

5. In a station-indicator, the combination, with the indicating apparatus, the air-cushion, with its piston and piston-rod, of the bracket pivoted at one end to the car-truck, the adjustable rod supporting its other end, and the controlling-spring around the rod, the chain-pulley carried by the bracket, the chain passing from the pulley to the piston-rod, the sector carried by the pulley and arranged to come in contact with and to roll on a fixed obstruction in the roadway, and the stop on the sector for limiting the return of the sector and pulley, substantially as herein described.

In witness whereof I have hereunto set my hand.

JOHN KNIGHT.
